UNITED STATES PATENT OFFICE.

EDWIN H. SMYTHE, OF EVANSTON, ILLINOIS, ASSIGNEE TO WESTERN ELECTRIC COMPANY, INCORPORATED, OF NEW YORK, N. Y., A CORPORATION OF NEW YORK.

AUTOMATIC TELEPHONE SYSTEM.

Application filed November 15, 1923. Serial No. 674,803.

To all whom it may concern:

Be it known that I, EDWIN H. SMYTHE, a citizen of the United States of America, residing at Evanston, in the county of Cook and State of Illinois, have invented certain new and useful Improvements in Automatic Telephone Systems, of which the following is a full, clear, concise, and exact description.

10 This invention relates to automatic telephone exchanges and more particularly to a trunk hunting switch for use in such systems.

15 Its object is to provide an improved and simplified circuit arrangement for switches of this character.

20 The invention contemplates a circuit arrangement wherein the automatic switch is advanced over trunk groups during cycles of operation of a control magnet armature, the cessation of movement of said armature causing means to be rendered operative to shift the control of the further movement of the switch to the multiple test terminals 25 of the selected trunk group.

Referring to the accompanying drawing which shows only so much of a telephone system as is necessary for a comprehension of the invention, the calling lines terminate 30 in line switches LS which may be of any well-known type, and these switches as well as the intermediate selectors are not shown in detail. The connector of this invention to which these selectors extend the calling line is of the single motion type, and is particularly adapted for and is shown in connection with private branch exchange working wherein each subscriber has a number of trunk lines terminating therein. The 35 groups of trunks are, therefore, arranged in the same level. Four rows of terminals are provided as shown, two of which are talking terminals and the other two are test terminals. The talking rows and the lowest row 40 only are multiplied to other connectors in the well-known manner.

It is thought that the invention will be most readily understood from a description of the operation of the system.

50 The calling subscriber at substation A initiates a call by removing his receiver, thus closing the line circuit which causes the line switch LS to plunge and seize a first selector. This selector and succeeding selectors are 55 then set in the well-known manner to seize

a rotary connector C whereupon the impulse relay 1 thereof operates over the calling line circuit. The impulse relay 1 at its outer armature operates slow to release relay 2, which at its left armature interposes a break in the circuit of release magnet 3. At its outer right armature, relay 2 applies a holding ground to release wire 4, thus holding the selectors and the line switch set in the well-known manner and placing a busy condition on the seized connector test multiple 5. Relay 2 at its inner right armature connects relay 7 to the back contact of the impulse relay 1. The connector is now ready to receive the impulses and, upon the return of the dial D at the calling substation for the last digit of the desired number, the line circuit is interrupted a number of times corresponding to such digit and the impulse relay 1 follows the impulses. Relay 2 remains operated during impulsive. Upon the first attraction of its armature, relay 7 closes a circuit to step the brushes 48, 47, 11 and 18, which move in unison, off normal, and to operate a slow to release relay 8 to energize the usual escape or side switch magnet 9. The circuit for relay 8 is as follows: grounded armature and alternate contact of relay 7, relay 8, normal terminal 10 of the connector group test brush 11, side switch arm 12, conductor 13, contact and winding of stepping magnet 32 to battery.

Upon the reclosure of the line by the dial D, relay 1 again energizes, releasing relay 7 which applies ground to terminal 14 on which the brush 11 is now resting. The application of this ground causes magnet 32 to step the brush 11 to the test terminal 15 of the first trunk over an obvious circuit, and if the digit transmitted consists of only one impulse the relay 7 will remain normal. Since the stepping magnet 32 cannot again operate until after relay 7 operates, brush 11 will remain on test terminal 15. Slow relay 8 releases after a slight interval and effects the change-over operation causing the connector to hunt for an idle private branch exchange trunk line in the first trunk group. The change-over is effected due to slow relay 8 retracting its armature, which opens the circuit of escape magnet 9, this circuit having been closed when relay 8 operated, due to the operation of relay 7 as described. In position 2, side switch arm 16 connects test relay 17 to individual test

brush 18. Busy trunks have their test multiples 19 grounded as will appear. Assuming the terminals 19 and 20 of the first and second trunks respectively of the group are grounded, test relay 17 in operating from these grounds closes a circuit, including side switch arm 21, for the stepping magnet 32 which advances the brushes 18 and 11 to terminals 22 and 23, respectively, and the talking brushes to the talking terminals 50 and 51 of the corresponding trunk. The brush 18 bridges its terminals. The escape magnet 9 is slow to operate and will not actuate its armature by the momentary flow of current it may get before test relay 17 operates. Relay 17 is designed to be fast to operate and to release. As soon as an idle trunk is found, the absence of ground on its test terminal 22 causes the test relay 17 to release, and its armature then applies ground to the escape magnet 9 for a sufficient period to energize the same. The escape magnet is constructed and arranged to move its arms from position 2 to position 3 upon energization. In this position, arms 24 and 25 extend the calling line through to the called line terminals. Current is supplied to the called line transmitter through impedance coil 42. Condensers 40 41 separate the calling and called current sources in the well-known manner. Side switch arm 16 in position 3 applies a direct ground to the multiple test terminals 22 of the seized line. The ringing circuits are not shown since they form no part of the invention and may be of any well-known type.

Assume, however, that the digit dialed is two instead of one. It will be remembered that brush 11 was advanced to the test terminal 15 when the line was again closed by the dial D, that relay 1 remained operated preventing the relay 7 from reoperating, and that in consequence, relay 8 and the escape magnet 9 released. If, however, another impulse is produced at the dial D, the line circuit is again opened, relay 1 releases and relay 7 again operates, thereby preventing relay 8 and consequently the escape magnet 9 from releasing.

The reoperation of relay 7 connects ground to terminal 15, thus closing the circuit to reoperate the stepping magnet 32, thereby advancing brush 11 to terminal 27 and brush 18 to terminal 20. It should be observed that until this second impulse is produced by the dial D, the stepping magnet 32 could not operate to advance the brushes 48, 47, 11 and 18, unless the trunk hunting movement was initiated by the release of the slow relay 8 and the escape magnet 9. With brush 11 resting on terminal 27, the circuit for the stepping magnet is opened awaiting the release of relay 7; hence the brushes 48, 47, 11 and 18 cannot advance. When the line is again closed at the dial D,

relay 1 reoperates and relay 7 releases. The release of relay 7 connects ground to the test terminals 27, 23, and 28 of the remaining trunks in the first trunk group, and the stepping magnet now operates and advances the brushes from one set of terminals to another until brush 11 is resting upon the test terminal 29 when the circuit through the stepping magnet is opened. Brush 11, accordingly, remains at rest upon test terminal 29 associated with the first trunk in the second group.

The dial D is designed so that the period of time during which the impulse springs of the dial are closed between breaks, is sufficient to permit the stepping magnet 32 to function and advance the brushes 48, 47, 11, and 18 from the terminals of the second line in a particular group to the terminal of the first line in the next succeeding group, before, by the release of the impulse relay 1 upon the succeeding break of the dial impulse springs, relay 7 reoperates to close the operating circuit for the stepping magnet 32, to further advance the brushes 48, 47, etc.

Relay 8 is designed to be slow to release so that it remains operated during the period that its operating circuit is open, namely, from the advance of the brush 11 from the first terminal (11, 15, 29, etc.) of a group until the reoperation of relay 7 on the next succeeding impulse produced by the dial D.

When advancing, brush 11 bridges adjacent terminals, but when centered it is in contact with only one of the terminals 10, 14, 15, etc.

After the last impulse in the train of impulses has been sent, in this case after the second impulse, the prolonged closure of the line by maintaining relay 1 operated, prevents relay 7 from reoperating; hence slow relay 8 now releases, permitting the escape magnet 9 to advance the side switch arms 24, 25, 12, 16, 21, etc., to position 2, in which position the trunk hunting movement of the connector is initiated.

In case all the trunks in the desired group are busy the switch will continue to step from grounds on the busy test multiples as described and will come to rest due to the test brush 18 reaching a non-multiplied or dead terminal 43, one of which follows each group. Due to brushes 47 and 48 resting on a corresponding pair of terminals 44, 45, to which a busy tone source 46 is permanently connected and due to side switch arms passing to position 3 when test brush 18 moved onto dead terminal 43, busy tone is applied to the calling line to notify the calling party that all the trunks are busy.

Release is effected by the replacement of the receiver by the calling party which, by opening the line circuit at the connector releases relay 1, thereby releasing slow relay

2. This relay at its left armature, and the armature of relay 1 closes the circuit of the release magnet 3, this circuit including off-normal contact 31. The release magnet 5 withdraws the holding pawls, and a restoring spring (not shown) restores the selector to its normal position. The side switch is restored by a mechanical connection between its arms and the release magnet armature in 10 the well-known manner.
- If the calling subscriber abandons the call before an idle trunk is selected the release of the impulse relay 1 and relay 2 operates the release magnet over an obvious circuit.
- 15 It should be understood that the number of trunks or lines in a group is not fixed but may be varied at will, some groups containing but few trunks or lines, and other groups containing a larger number. It is also evident that the trunks are designated by their group number and not by individual trunk numbers, or expressed in another way, it may be considered that the first trunk in each group is designated by a distinguishing 20 number, and that the remaining trunks in each group are unnumbered lines.
- What is claimed is:
1. An automatic switch responsive to impulses, comprising sets of terminals arranged in groups and brushes capable of passing over said terminals, means responsive to an impulse for initiating the advance of the switch brushes preparatory to seizing the first set of terminals in a group, and 25 means effective between impulses of the same impulse train for continuing to advance the switch brushes to the first set of terminals of the group.
2. An automatic switch, responsive to impulses, having a group hunting movement, comprising sets of trunk terminals arranged in groups, brushes capable of hunting over said terminals, means responsive to an impulse for initiating the group hunting movement of the switch brushes, means effective between impulses for advancing the switch brushes to the first set of trunk terminals in the first trunk group, and means responsive to another impulse of the same impulse train 30 for passing over all the sets of trunk terminals in the first trunk group and for continuing the group hunting movement.
3. An automatic switch, responsive to impulses, having a group hunting movement, comprising sets of trunk terminals arranged in groups, brushes capable of hunting over said trunk terminals, means responsive to an impulse for initiating the group hunting movement of the switch brushes, means effective between impulses for advancing the switch brushes to the first set of trunk terminals in a group, and means for initiating the trunk hunting movement of the switch brushes providing the last impulse of the 35 train of impulses has been transmitted.
4. In a telephone system, a progressively movable selecting switch having both a group hunting and a trunk hunting movement, an impulse sender, a circuit including the switch and sender, means controlled by the impulse sender for initiating the group hunting movement of said switch, means for continuing said movement after the last impulse of a train of impulses has been transmitted by the impulse sender, and means effective thereafter for initiating the trunk hunting movement of the switch.
5. In a telephone system, a selector switch having both a group hunting and a trunk hunting movement with access in one level to successive groups of trunks, an impulse sender, a circuit including said switch and sender, means responsive to a train of impulses produced by the impulse sender for initiating the group hunting movement of said switch, means for continuing said movement irrespective of the busy or idle condition of the trunks passed over until after the last impulse of the train of impulses has been transmitted, and means effective thereafter for initiating the trunk hunting movement of the switch.
6. In a telephone system, an impulse relay, an automatic switch controlled thereby having trunk groups, a relay connected to a back contact of the impulse relay and operated by the release of the impulse relay to start said switch over a trunk group, the subsequent energization of the impulse relay releasing said relay to continue the movement of the switch over said group.
7. In a telephone system, a control circuit including a magnet, an automatic switch controlled thereby, means constructed and arranged to start said switch on an automatic hunting movement upon the movement of the armature of said magnet in one direction and means to continue the advance of said switch upon the movement of the armature in the other direction.
8. In a telephone system, an automatic switch having trunk terminals arranged in groups, the groups all arranged in a single row, a circuit including a calling line an impulse sender and the impulse relay of said automatic switch, means for starting said automatic switch in motion as soon as the sender begins to interrupt said circuit, means including a contact of the impulse relay and terminals of said automatic switch for designating the group of trunks in which the automatic switch is to commence hunting, and means including multiple test terminals of the said group for controlling further movement of the automatic switch.
9. In a telephone system, a single motion connector having groups of multiple trunk terminals and a row of multiple test terminals, trunk lines connected thereto, a telephone line, an impulse sender thereat, a cir-

- cuit including said line, said sender and the impulse relay of the connector, means associated with said connector and constructed and arranged to advance said connector onto the first trunk of the first group on the first interruption and reclosure of said circuit by the sender and on the next interruption and reclosure to advance the connector over all trunks in the first group and onto the first trunk in the second group, and circuits including the multiple terminals of said second group of trunks for causing the connector to pass over busy trunks and come to rest on the first idle trunk.
15. In a telephone system, a connector having groups of multiplied talking trunk terminals in a single row, a row of non-multiplied terminals in said connector, a row of multiple test terminals, a circuit including a calling line an impulse sender and the impulse relay of said connector, a circuit including a contact closed by the first release of the impulse relay armature, the first terminal in the row of non-multiplied terminals and a brush of the connector for stepping the connector off the first terminal, a circuit including a contact closed by the next attraction of the impulse relay armature, the second terminal in the row of non-multiplied terminals and said brush for stepping the connector onto the first trunk in the first group, a circuit including a contact closed by the next release of the impulse relay armature, the third of said non-multiplied terminals and said brush for stepping the connector off the said first trunk, circuits including a contact closed by the next attraction of the impulse relay armature, all the non-multiplied terminals of the first trunk group and said brush for stepping the connector to the first non-multiplied terminal apportioned to the next trunk group, and circuits for continuing the movement of the connector and dependent upon the busy condition of the multiplied test terminals of the selected group.
11. In a telephone system, a selector switch having both a group hunting and a trunk hunting movement with access in one level to consecutively numbered groups of trunks, a calling line equipped with an impulse sender having access to the trunks via the switch, a circuit including said switch and impulse sender, means responsive to an impulse for initiating the group hunting movement of said switch, means for continuing said movement between impulses irrespective of the busy or idle condition of the trunks in the groups passed over until after the last impulse of an impulse train has been transmitted when the switch will be set upon the first trunk of the selected group, means effective thereafter for initiating the trunk hunting movement of the switch, and means effective if all trunks in the selected trunk group are busy for indicating the busy condition thereof to the calling line.
12. An automatic switch, set responsive to impulses, having both a group hunting and a trunk hunting movement, means responsive to an impulse for initiating the group hunting movement, means effective between impulses for continuing the group hunting movement, the group selected depending upon the number of impulses transmitted, and means for beginning the trunk hunting movement after the proper group has been selected.
13. An automatic switch, set responsive to impulses, having a group hunting movement followed by a trunk hunting movement, means responsive to an impulse for initiating the group hunting movement, and means effective between impulses for continuing the group hunting movement, the group selected depending upon the number of impulses transmitted.
14. An automatic switch, set responsive to impulses, having a group hunting movement followed by a trunk hunting movement, means responsive to an impulse for initiating the group hunting movement, and means effective between impulses for continuing the group hunting movement, the group selected varying in accordance with the number of impulses transmitted.
15. In a telephone system, a traveling switch controlled by impulses, and means changeable at will for varying the extent of the switch movement per impulse.
16. In a telephone system, a connector switch, consecutively numbered groups of subscribers' lines connected to said switch, said groups being serially arranged and variable in size, and means operable to select any desired group and to seize the first idle line therein.
17. In a telephone system, a single motion connector switch, consecutively numbered groups of subscribers' lines connected to said switch, said groups being serially arranged and variable in size, and means operable to select any desired group and to seize the first idle line therein.
18. In a telephone system, a selector switch, consecutively numbered and serially arranged groups of lines connected to said switch, each group comprising a plurality of unnumbered lines and a single numbered line, means operable to select a numbered line, and means effective thereafter to seize the first idle line in the group selected.
- In witness whereof, I hereunto subscribe my name this 10th day of November, A. D. 1923.

EDWIN H. SMYTHE.
